UNITED STATES PATENT OFFICE

145,564

DESIGN FOR A RUG AND UPHOLSTERY EXTRACTION MACHINE

Truman W. Doyle, Los Angeles, Calif.

Application October 2, 1945, Serial No. 122,470

Term of patent 7 years

(Cl. D9—2)

To all whom it may concern:

Be it known that I, Truman W. Doyle, a citizen of the United States of America, residing in the city of Los Angeles, in the county of Los Angeles, State of California, have invented a new, original, and ornamental Design for a Rug and Upholstery Extraction Machine, of which the following is a specification, reference being had to the accompanying drawings, forming a part thereof.

stery extraction machine showing my new design; Figure 2 is a side elevational view thereof;

Figure 4 is a front perspective view thereof on an enlarged scale in comparison with the other disclosures.

I claim:

The ornamental design for a rug and upholstery extraction machine, substantially as shown.

TRUMAN W. DOYLE.
